SHEET FEEDING APPARATUS

Leo C. Williams, Pearl River, N. Y., assignor to
Dexter Folder Company, Pearl River, N. Y., a
corporation of New York

Application October 4, 1939, Serial No. 297,799

14 Claims. (Cl. 271—62)

This invention relates to sheet feeders and while capable of general use is more particularly adapted for embodiment in feeders for feeding sheets of paper, tin, cardboard or other materials to various types of machines acting upon such sheets.

One object of the present invention is to provide an improved sheet feeder the sheet feeding action of which is automatically controlled by the elevator operating mechanism in such manner as to discontinue said action about or just prior to the time the pile or supply of sheets on the elevator has been exhausted.

Another object of the present invention is to provide an improved sheet feeder wherein the pile elevator, when rapidly lowered by power for loading or reloading purposes, may be automatically stopped when it reaches the loading position.

These and other objects of the present invention will appear as the following description thereof proceeds and in order to more clearly understand said invention reference may be had to the accompanying drawings which illustrate one embodiment thereof.

In said drawings:

Fig. 1 is a side elevation of a feeder embodying the present invention;

Fig. 2 is a front elevation of the feeder shown in Fig. 1;

Fig. 3 is an enlarged detail view, partly in section, of a pile elevator and feeder stopping device shown in Fig. 1, and illustrating diagrammatically an electric circuit for said device; and

Fig. 4 is an enlarged detail view, partly in section, of said stopping device looking from the right of Figs. 1 and 3.

Referring to the drawings, wherein like reference characters designate like parts throughout the several views, the various movable parts of the feeder as well as certain stationary parts thereof may be mounted on a frame of any suitable construction and the movable parts employed during normal operation of the feeder may be actuated or driven by any suitable means. As herein shown, said frame and driving means are preferably constructed as follows.

The feeder frame is comprised by front uprights 5 and rear uprights 6 connected together by side members 7 and 8 (Figs. 1 and 2). The uprights 5 and 6 are bolted or otherwise suitably secured to the machine foundation, the front uprights 5 being connected together by cross members 9 bolted or otherwise suitably secured thereto, and the rear uprights 6 being connected together at

the tops thereof by a stay shaft 10. The cross members 9 have bolted or otherwise suitably secured thereto a metal apron or plate 11 against which the front side of a pile or supply of sheets 12 bears during elevation of the same by mechanism to be hereinafter described.

Referring now more particularly to Fig. 2, the drive for the feeder is preferably comprised by a chain 13 driven from any suitable source of power (not shown) and passing around a sprocket 14 which is fixed on a short shaft 15. This short shaft 15 is journaled in a suitable bearing in the adjacent front upright 5 and has also fixed thereon a spur pinion 16. Spur pinion 16 meshes with a spur gear 17 which is fixed on a transversely extending cam shaft 18 that is journaled in suitable bearings in the front uprights 5 and is utilized to operate various parts of the feeder to be hereinafter described. The feeder includes a pile elevator and operating mechanism therefor preferably constructed as follows.

Fixed on the short shaft 15 is a crank disk 19 having pivotally connected therewith one end of a link 20 the opposite end of which is pivotally connected with a pawl carrier 21. The pawl carrier 21 is loosely mounted on a shaft 22 (Figs. 1 and 2) which extends transversely of the feeder and is journaled in suitable bearings on the front uprights 5. Shaft 22 is intermittently operated to raise the pile elevator hereinafter described and said operation is preferably effected by pawl and ratchet mechanism of the general type disclosed in the United States Patent No. 2,149,130 granted February 28, 1939, to Leonard Baker.

This pawl and ratchet mechanism includes the pawl carrier 21 and a pawl 23 pivoted thereon and adapted, under certain conditions, to engage a ratchet 24 which is fixed on the shaft 22. It will thus appear that through oscillation of the pawl carrier 21 by the described driving connections therewith the chain 13 and through engagement of the pawl 23 with the ratchet 24, the shaft 22 will be intermittently rotated as stated above. Under these conditions left and right hand worms 25 and 26 (Fig. 2) fixed on opposite ends of shaft 22 will likewise be rotated. These worms 25 and 26 mesh with left and right hand worm gears 27 and 28 which are fixed on shafts 29 and 30, respectively, that extend longitudinally of the feeder at opposite sides thereof and are journaled in suitable bearings on the front and rear uprights 5 and 6.

Fixed on shafts 29 and 30 are toothed sheaves 31 (Figs. 1 and 3) in the teeth of which are engaged links of chains 32 that are connected at

their lower ends by couplings 33 with a pile elevator comprising cross beams 34. The elevator 34 has placed thereon a pile board 35 which, together with the pile of sheets 12, is positioned on said elevator through the rear of the feeder when the elevator is lowered by means for this purpose hereinafter described. It will be noted that the shafts 29 and 30 are rotated in opposite directions away from each other when the elevator is raised, 10 and rotated in opposite directions toward each other when the elevator is lowered.

The elevator 34 and pile of sheets 12 thereon are raised intermittently as the sheets are fed off the top of the pile by sheet separating and forwarding devices hereinafter described, and to keep the top of said pile at the proper feeding level the elevator and its operating mechanism are preferably controlled by pneumatic means comprising a pile governor 36, a mask 37 and a 20 mask detent 38 preferably mounted, constructed and operated as disclosed in the United States Patent No. 2,156,648 granted May 2, 1939, to Leonard Baker, George A. Martin and Leo C. Williams and needing no detail description 25 herein.

The feeder is provided with means for supplying air under pressure to pile and sheet winding devices, means for creating vacuum in the sheet separating and forwarding devices, and means 30 for lowering and raising the pile elevator for loading and reloading purposes, and said means are preferably mounted, constructed and operated as follows. Extending transversely of the feeder and secured in any suitable manner in the front 35 uprights 5 are shafts 39 (Figs. 1 and 2) which have bolted or otherwise suitably secured thereto a pair of spaced brackets 40. Bolted or otherwise suitably secured to the spaced brackets 40 is an electric motor 41. Fixed on the armature shaft 40 42 of motor 41 is a sprocket 43 around which passes a chain 44 that also passes around a sprocket 45. This sprocket 45 is fixed on one end of a shaft 46 which, in turn, is connected by a coupling 47 with the shaft 48 of a pump 49 (Fig. 2) suitably constructed to supply air under pressure from one side thereof and to create vacuum in another side thereof.

The pump 49 is bolted or otherwise suitably secured to a pair of spaced brackets 50 which are 50 bolted or otherwise suitably secured on one of the cross shafts 39 and a third cross shaft 51 that is secured in any suitable manner in the front uprights 5. Connected with the air pressure side of pump 49 is one end of a conduit 52 the opposite 55 site end of which is connected with a compressed air tank 53 that is secured in any suitable manner on the feeder frame.

The compressed air tank 53 has connected therewith one end of a conduit 54 the opposite 60 end of which is connected with one part 55 of a tubular shaft indicated broadly at 56 (Fig. 2) which extends transversely of the feeder and is secured in any suitable manner in the front uprights 5 near the tops thereof. The tubular 65 shaft 56 is centrally divided to form the air conduit 55 and a vacuum conduit 57. The vacuum conduit 57 has connected therewith one end of a conduit 58 the opposite end of which is connected with the vacuum side of pump 49. The 70 conduits 55 and 57 are connected with the air and vacuum sides, respectively, of a valve mechanism indicated broadly at 59 which, through the described connections therefor with the pump 49, controls delivery of air under pressure to pile 75 and sheet winding devices, and the making and

breaking of vacuum in sheet separating and forwarding devices hereinafter referred to. The mounting, construction, and operation of this valve mechanism is the same as that of the valve mechanism disclosed in the above mentioned 5 United States Patent No. 2,156,648 and needs no detail description herein.

Mounted on the feeder frame and secured thereto in any suitable manner, is an auxiliary frame 60 (Fig. 1) comprised by side members 61 10 and a cross member 62 adjustable along said side members to various positions. The cross member 62 has mounted thereon the pile governor 36, the pile and sheet winding devices 63 and 64, respectively, and the sheet separating devices comprised 15 by cylinders 65 and rubber suction cups 66 that are raised and lowered through the making and breaking of vacuum in said cylinders. The construction and operation of these sheet separating devices is the same as the construction and 20 operation of the sheet separating devices disclosed in the United States Patent No. 2,156,648 above referred to and need no further detail description herein. It might be pointed out, however, that the cylinders 65 are connected by flexible conduits 67 with the vacuum side of the valve mechanism 59 which controls the making and 25 breaking of vacuum in said cylinders at predetermined intervals. Likewise, the pile and sheet winding devices 63 and 64, respectively, are connected by flexible conduits 68 and 69, respectively, with the air side of the valve mechanism 59 which controls the delivery of air under pressure to 30 said pile and sheet winding devices at proper intervals. 35

The separated and wined sheets are forwarded one after another from the top of the pile by sheet forwarding devices comprised by cylinders 70 (Figs. 1 and 2) and rubber suction cups 71 which are raised and lowered through the making and breaking of vacuum in said cylinders. These sheet forwarding devices are also constructed and operated in the same manner as the sheet forwarding devices disclosed in the United States Patent No. 2,156,648 referred to 45 above and need no detail description herein. It is pointed out, however, that sheet forwarding devices have swinging movement to advance the sheets from the pile 12, and for this purpose the cylinders 70 are secured to arms 72 which, in 50 turn, are fixed on a rock shaft 73 that extends transversely of the feeder frame and is journaled thereon in any suitable manner. The sheet forwarding devices are rocked forwardly by a cam 74 (Fig. 2) fixed on the cam shaft 18, and said sheet 55 forwarding devices are rocked rearwardly by a spring (not shown). The cam 74 engages a roller 75 which is journaled on one end of a cam strap 76 extending over the cam shaft 18. The opposite end of the cam strap 76 is pivotally connected with an arm 77 which is fixed on the rock shaft 73. 60

The cylinders 70 of the sheet forwarding devices have connected therewith corresponding ends of flexible conduits 78 the opposite ends of which are connected with the vacuum side of the valve mechanism 59 which also controls the making and breaking of vacuum in said cylinders at predetermined intervals. 65

The sheets separated from the pile 12 by the sheet separating devices are taken by the sheet forwarding devices and delivered thereby to a sheet conveyor which advances the sheets to the machine with which the feeder is associated. As herein shown, this conveyor includes spaced 75

feed rollers 79 around which pass a plurality of conveyor tapes 80 that also pass around a front conveyor roller (not shown). The feed rollers 79 are secured in any suitable manner to a shaft 81 which extends transversely of the feeder and is journaled in suitable bearings in the front uprights 5. The shaft 81 is driven from the short shaft 15 by a spur gear 82 fixed on said short shaft and which meshes with a spur pinion 83 that is fixed on the shaft 81. Cooperating with a pair of the feed rollers 79 are drop rollers 84 which are journaled on arms 85 (Fig. 2) that are adjustably secured to a rock shaft 86 extending transversely of the feeder frame and journaled thereon in any suitable manner. The drop rollers 84 are raised and lowered at certain intervals through the action of a cam 87 which is secured to or formed integrally with a valve driving disk 88 that is fixed on the cam shaft 18 and forms part of the valve mechanism 59. The cam 87 engages a roller 89 which is journaled on an arm 90 that is fixed on the rock shaft 86.

In the normal operation of the feeder the sheets are separated and forwarded from the pile by the sheet separating and forwarding devices and delivered by the latter to the conveyor which advances the sheets to the machine to be fed. As the sheets are so separated, forwarded and conveyed, the pile elevator is raised intermittently to compensate for removal of the sheets from the pile and to maintain the top of the latter at the proper feeding level for the operation of the sheet separating and forwarding devices. This intermittent elevation of the pile elevator is effected through the described driving connections for the elevator with the chain 13 which connections include the pawl and ratchet mechanism 23, 24 utilized for driving the elevator operating shaft 22 and the operation of which, in turn, is controlled by the pneumatic pile governor 36. The casing for the pneumatic governor 36 is connected by a flexible conduit 91 with the air supply conduit 55 and said casing 45 is further connected by a flexible conduit 92 with the casing for the detent 38. This detent 38 through raising and lowering movement in accordance with the raising and lowering movement of the governor 36, controls the movement 50 of the pawl mask 37 which, in turn, controls the operation of the pawl and ratchet mechanism 23, 24 and the intermittent upward movement of the pile elevator, all as described in the United States Patent No. 2,156,648 above referred to.

55 During normal operation of the feeder, the pump 49 is driven by the motor 41 to supply air under pressure to the pile and sheet winding devices 63 and 64, respectively, and to create vacuum in the cylinders 65 and 70 of the sheet separating and forwarding devices, respectively. The motor 41 is of the three phase type supplied with current from any suitable source through lead wires 93, 94 and 95 (Fig. 3). Wire 93 is connected by a wire 96 with one terminal of a normally open motor starting switch 97 of the push button type. This switch 97 is arranged in a switch box 98 indicated in broken lines in Fig. 3 and mounted by suitable means at any convenient point on the feeder frame. The other terminal 65 of the switch 97 is connected by a wire 99 with a coil 100 of a magnetic switch 101 arranged in a control box 102 indicated in broken lines in Fig. 3 and secured by suitable means at any convenient point on the feeder frame.

70 75 The coil 100, in turn, is connected by a wire

103 with the wire 95 and it will thus appear that when the switch 97 is closed by the machine attendant, the coil 100 will be energized and actuate switch 101 to close it in contact with terminals 104, 105 and 106 of wires 93, 94 and 95. 5 Closing of the switch 101 starts the motor 41 which receives current from wires 93, 94 and 95 through wires 107, 108 and 109 which are connected with said switch and with said motor. The switch 97, having been closed by the machine attendant, is opened as soon as he releases it, thus disconnecting the wires 96 and 99. The wire 99, however, which is connected with the switch 97 and the coil 100, is also connected with the switch 101 by a wire 110. When the switch 101 is closed, the wire 110 is connected by said switch with the terminal 111 of a wire 112 which is connected with one terminal of a normally closed stop switch 113 (Figs. 1, 3 and 4). This switch 113 is of the push button type and is arranged in a switch box 114 that is suitably secured to a plate 115 which, in turn, is bolted or otherwise suitably secured to the side member 8.

The other terminal of the switch 113 is connected by a wire 116 with one terminal of a second normally closed stop switch 117 of the push button type and arranged in the switch box 98. The other terminal of the switch 117 is connected by a wire 118 with the wire 96 which, as previously described, is connected with the lead wire 93. It will thus appear that when the switch 97 is released by the machine attendant and opened disconnecting the wires 96 and 99, the coil 100 receives current from the lead wire 93 through wires 96 and 118, switch 117, wire 35 116, switch 113, wire 112, terminal 111 and wires 110 and 99. The coil 100 thus continues to be energized and maintains the switch 101 closed, regardless of the opening of the switch 97. It will further appear, that when the switch 113 40 or 117 is actuated to open the same, the previously described current for maintaining the coil 100 energized is broken causing said coil to be deenergized thus opening the switch 101 and stopping the motor 41.

In accordance with the present invention the feeder is provided with means for stopping the sheet feeding operation when a supply of sheets elevated intermittently by the mechanism described for this purpose is nearly exhausted. Said means stops the pump 49 and prevents further operation of the sheet separating and forwarding devices which, if allowed to continue in operation when the pile is completely exhausted, might cause trouble in the feeder and damage to said devices. Said feeder stopping means is preferably mounted, constructed and operated as follows.

Fixed on the elevator chain shaft 30 as by a set screw 119 is an externally threaded cylinder 60 65 120 (Figs. 1, 3 and 4). This cylinder 120 is positioned on the shaft 30 between the sheaves 31 thereon and above the switch supporting plate 115. Cooperating with the threaded cylinder 120, and movable therealong through rotation of said cylinder, is an internally threaded collar 121 having a flattened portion 122 on the underside thereof. Rotation of the collar 121 relative to the cylinder 120 is prevented by the upper end of the plate 115 which projects into a groove 123 formed in 70 said collar.

Pivots mounted on a pin 124 suitably secured in the plate 115 at the upper end thereof is an arm 125 which is spaced outwardly from said plate and extends beneath the flattened portion 75.

122 of the collar 121. The arm 125 is retained against displacement from the pin 124 by a cotter pin 126. Adjustably secured to one side of the arm 125 and adjacent the pin 124 is a block 127 provided with an elongated slot 128 through which passes a bolt 129 that is threaded in a suitable opening in said arm. The upper side of the block 127 is formed with a cam track 130 which extends in the path of movement of the collar 121 to be engaged by the flattened portion 122 thereof.

Pivottally mounted on a pin 131 and at the opposite end and one side of the arm 125 is a trigger 132 which normally rests by gravity on the push button 133 of the switch 113. The pin 131 is secured in any suitable manner on the arm 125 and endwise displacement of the trigger 132 on said pin is prevented by a cotter pin 134. The trigger 132 is held in its normal vertical position by a pull spring 135 one end of which is engaged over a pin 136 secured in said trigger, the opposite end of said spring being connected at 137 with the block 127. Rotation of the trigger 132 by the spring 135 beyond the normal vertical position is prevented by a stop pin 138 which is secured in said trigger and engages the under side of the arm 125.

It will thus appear that when the chain shafts 29 and 30 are intermittently rotated during normal operation of the feeder to raise the elevator and keep the top of the pile of sheets thereon at the proper feeding level, the shaft 30 and threaded cylinder 120 thereon are rotated in the direction of the arrow U (Fig. 4). This rotation of shaft 30 and cylinder 120 causes the collar 121 to move along said cylinder in the direction of the arrow U' (Fig. 3) until the flattened portion 122 of said collar engages the cam track 130 on the block 127. Engagement of the cam track 130 as aforesaid occurs when only a few sheets of the supply remain on the elevator at which time the collar 121 depresses the arm 125, trigger 132 and push button 133 and thus opens the switch 113. Opening of the switch 113 breaks the circuit to coil 100 that includes the wires 93, 96, 118, the switch 117, the wires 116, 112, the terminal 111, and wires 110 and 99. This circuit being broken, the coil 100 is deenergized, the switch 101 is opened, and the motor 41 and the pump 49 are stopped. Stopping of the pump 49 renders the sheet separating and forwarding devices ineffective to separate and forward the remaining sheets on the elevator. This, in turn, prevents further operation of the governor 36 and further raising of the elevator. It will further appear that the sheet feeding operation may be stopped with more or less sheets remaining on the elevator, as desired, by loosening the bolt 129 and sliding the block 127 in opposite directions on the arm 125. When the block is moved to the right (Fig. 3) more sheets will remain on the elevator, and when the block is moved to the left less sheets will remain on the elevator.

In accordance with the present invention means are provided to rapidly lower the elevator in order to load or reload it and to stop said elevator in a predetermined lowered position in order to prevent overrunning of the chains 32 and disengagement of the same from the sheaves 31. Said means are preferably mounted, constructed and operated as follows and includes the trigger 132 and the switch 113. Upon the stopping of the sheet feeding operation before the supply on the elevator is completely exhausted, as previously described, the machine attendant grips the trigger 132 and turns it clockwise (Fig. 3) against the tension of the spring 135 until said trigger clears

the push button 133 of the switch 113. The switch 113, through the action of a spring (not shown) is then closed whereupon the switch 97 is again pushed by the machine attendant to start the motor 41 in the manner previously described. Starting of the motor 41, of course, starts the pump 49 through rotation of the shaft 46 which, as previously described, is connected with said motor and said pump. The shaft 46 forms part of a power mechanism for rapidly raising and lowering the elevator for loading and reloading purposes, and said mechanism is preferably mounted, constructed and operated as follows.

Secured in any suitable manner in spaced relation on the uppermost cross shaft 39 and the cross shaft 51 are brackets 139 (Figs. 1 and 2) which have bolted or otherwise suitably secured thereto in spaced relation plates 140 provided therein with bearings for the shaft 46 and through which said shaft extends. Mounted in spaced relation on the shaft 46 between the plates 140 are clutches 141 and 142 of well known construction and a clutch engaging and releasing device 143 therebetween provided with a grooved collar 144. The clutch 141 has a part 145 fixed on the shaft 46 and a part 146 loose on said shaft and provided with a spur pinion 147. The spur pinion 147 meshes with a similar pinion 148 which is journaled in any suitable manner on one of the plates 140. This pinion 148 meshes with a small spur gear 149 which is fixed on a shaft 150 journaled in suitable bearings in the plates 140. The clutch 142 has a part 151 fixed on the shaft 46 and a part 152 loose on said shaft and provided with a spur pinion 153. The spur pinion 153 meshes with a large spur gear 154 that is fixed on the shaft 150. The shaft 150 projects outwardly through the outermost plate 140 and fixed on the projecting end of said shaft is a sprocket 155 around which passes a chain 156 that also passes around a sprocket 157 (Fig. 1) that is fixed on the outwardly projecting end of the shaft 22.

Bolted or otherwise suitably secured at one side of the feeder on the adjacent uprights 5 and 6 are brackets 158 (Fig. 1) in which is journaled a rock shaft 159 having fixed on the rear end thereof a handle 160. Fixed on the front end of the rock shaft 159 is an arm 161 (Fig. 2) having pivotally connected therewith the upper end of a rod 162. The lower end of rod 162 is pivotally connected with one arm 163 of a bell crank 164 which is pivotally mounted on an arm 165 that is fixed in any suitable manner between the plates 140 on a stay shaft 166 (Figs. 1 and 2) which connects said plates together. The other arm 167 of bell crank 164 is pivotally connected as by a pin and slot connection 168 with a fork 169 that is engaged in the groove 144 of the clutch engaging and releasing device 143. The rock shaft 159 has also fixed thereon an arm 170 having a pin and slot connection 171 with one end of a shift rod 172, which extends transversely of the feeder and is slidably mounted in suitable bearing on the front uprights 5. Fixed on the shift rod 172 is a fork 173 which is engaged in a groove 174 formed in the pawl mask 31. The shift rod 172 and the handle 160 are normally maintained in the inoperative full line positions thereof shown in Fig. 2 by a spring 175 that is mounted on said shift rod between a collar 176 thereon and the adjacent front upright 5. In the inoperative positions of the handle 160 and shift rod 172, and during normal operation of the feeder, the parts 165, 146 and 151, 152 of

clutches 141 and 142, respectively, are disconnected.

When the sheet feeding operation is automatically stopped and the switch 113 is again closed as previously described, the machine attendant pushes switch 97 to start the motor 41 and then moves the handle 160 to the left as viewed in Fig. 2. When the handle 160 is moved to the left (Fig. 2) the shift rod 172, the fork 173, and the mask 37 are moved to the right so that said mask lifts the pawl 23 and holds it out of engagement with the ratchet 24. Upon shifting of the handle 160 to the left (Fig. 2), the rod 162 and arm 163 are raised, thus moving the arm 167 and fork 169 to the right (Fig. 2) and connecting the parts 145, 146 of clutch 141. When the two parts of clutch 141 are connected as above described, the shaft 22 is continuously and rapidly driven by the motor 41 through clutch 141, gears 147, 148 and 149, and chain 156 and the elevator and pile the sheets thereon are rapidly raised.

The elevator, upon rapid lowering thereof may be stopped when it reaches the machine foundation or a predetermined lowered position by the machine attendant moving the handle 160 to its full line inoperative position which action throws the clutch 141 out of operation and disconnects the drive from the motor 41 to the shaft 22. At the same time, the shift rod 172 is moved to the left (Fig. 2) by the expanding action of the spring 175 thereon and the mask 37 is moved thereby back to its operative position. The machine attendant then actuates switch 117 to open it and thus deenergize coil 100 so that switch 101 is opened and the motor 41 and pump 49 is stopped while a pile of sheets is loaded on the elevator. Switch 117 closes when released by the machine attendant but at this time switch 97 is open and switch 101 will not be actuated to start motor 41.

If, for any reason, the machine attendant fails to move the handle 160 as aforesaid and stop the elevator when it reaches its proper lowered position for loading or reloading, means are provided in accordance with the present invention to automatically perform this function and said means are preferably mounted, constructed and operated as follows.

When the elevator is rapidly lowered by the motor 41 as previously described, the chain shaft 30 and threaded cylinder 120 thereon are rotated in the direction of the arrow D (Fig. 4). As the elevator begins to lower, the collar 121 moves along the cylinder 120 in the direction of the arrow D' (Fig. 3) and out of engagement with the cam track 130 on the block 127. Disengagement of the cam track 130 as aforesaid, allows the spring 135 to return the arm 125 and trigger 132 to their normal full line positions as shown in Fig. 3, the arm 125 moving upwardly and the trigger 132 turning in a counter-clockwise direction and into engagement with the push button 133 of the switch 113. Continued lowering of the elevator and rotation of the chain shaft 30 and cylinder 120 moves the collar 121 further along said cylinder until the flattened portion 122 engages a cam track 177 that is formed on the free end of the arm 125 at the upper side thereof. Engagement of the cam track 177 by the collar 121, which occurs when the elevator reaches its proper loading or reloading position, depresses the arm 125, trigger 132, and push button 133 so that the switch 113 is opened and stops the motor 41 in the manner previously described.

The elevator having been lowered and stopped in its proper predetermined position for loading

or reloading, and a pile of sheets having been placed on the elevator, the latter and the pile of sheets are rapidly elevated until the top of the pile is brought into proper position for the normal sheet feeding operations. Accordingly, the machine attendant first closes the switch 113 in the manner previously described and then pushes the switch 97 to start the motor 41 and pump 49. Upon starting of the motor 41 the machine attendant moves the handle 160 to the right (Fig. 2) so that the rod 162 and arm 163 are lowered, thus moving the arm 167 and fork 169 to the left (Fig. 2) and connecting the parts 151 and 152 of clutch 142. When the two parts of clutch 142 are connected as above described, the shaft 22 is continuously and rapidly driven by the motor 41 through clutch 142, gears 153 and 154, and chain 156 and the elevator and pile the sheets thereon are rapidly raised.

As the top of the rapidly raising pile approaches the proper feeding level the elevator is stopped by the machine attendant moving the handle 160 to its inoperative position which action throws the clutch 142 out of operation and disconnects the drive from the motor 41 to the shaft 22. Normal operation of the feeder may now be resumed in the manner previously described through intermittent elevation of the elevator and pile of sheets, action of the sheet separating and forwarding devices, and operation of the pump 49 by the motor 41.

It is to be noted, that when the elevator and pile of sheets thereon are rapidly raised by the motor 41 as previously described, the chain shaft 30 is again rotated in the direction of the arrow U (Fig. 4) and that as the elevator begins to raise, the collar 121 through rotation of the cylinder 120 is moved in the direction of the arrow U' (Fig. 3) and out of engagement with the cam track 177. Disengagement of the cam track 177 as aforesaid, permits resetting of the arm 125 and trigger 132 so that the switch 113 may again be opened to stop the motor 41 and pump 49, in the manner previously described, when the pile of sheets is nearly exhausted.

The operation of the feeder embodying the present invention will be clearly understood from the foregoing description and while said description and the accompanying drawings set forth with more or less particularity one embodiment of the invention, it is to be expressly understood that said invention is not limited to said embodiment or otherwise than by the terms of the appended claims.

What I claim is:

1. In a sheet feeder having sheet feeding means, a pile elevator, and mechanism including a driven shaft for intermittently raising the elevator and pile during feeding of sheets from the top of said pile by said sheet feeding means, motor driven means for rendering the sheet feeding means effective to feed sheets from the top of the pile as aforesaid, and means on said driven shaft for throwing said motor driven means and the sheet feeding means out of operation when the elevator reaches a certain height and prior to feeding of all the sheets therefrom.

2. In a sheet feeder having suction sheet feeding means, a pile elevator, and mechanism including a driven shaft for intermittently raising the elevator and pile during feeding of sheets from the top of said pile by said suction sheet feeding means, motor driven vacuum pump means for rendering the suction sheet feeding means effective to feed sheets from the top of the pile

as aforesaid, and means on said driven shaft for throwing said motor driven pump means and said suction sheet feeding means out of operation prior to feeding of all of the sheets from said pile.

5. 3. In a sheet feeder having pneumatic means for acting on the sheets and a pile elevator cooperating with the pneumatic means and including a driven shaft, a device for throwing said 10 pneumatic means out of operation when the pile elevator reaches a predetermined position, and means mounted on and actuated by said driven shaft for operating said device.

4. In a sheet feeder having pneumatic sheet 15 handling means, a pile elevator, and means for raising said elevator, a device for throwing said pneumatic sheet handling means out of operation when the elevator is raised to a predetermined position, and means for actuating the 20 device comprising driven threaded means and an element cooperating with said driven threaded means and movable therealong through rotation thereof into engagement with said device.

5. In a sheet feeder having pneumatic sheet 25 handling means, electric motor driven pump means connected therewith, a pile elevator and a driven shaft therefor, the combination of means for supplying current to the electric motor of said pump means and comprising a circuit therefor, a device in the circuit for breaking it to thereby stop the motor and pump and the sheet handling action of said sheet handling means, and means mounted on and actuated by the 30 driven pile elevator shaft for operating said 35 device and breaking said circuit when the elevator has been raised to a predetermined position by said shaft.

6. In a sheet feeder having pneumatic sheet 40 handling means, electric motor driven pump means connected therewith, a pile elevator and a driven shaft therefor, the combination of means for supplying current to the electric motor of said pump means and comprising a circuit therefor, a switch in the circuit for breaking it to thereby stop the motor and pump and the sheet 45 handling action of said sheet handling means, a threaded cylinder mounted on and rotated by the driven pile elevator shaft, and a collar mounted on said cylinder and movable therealong through rotation thereof for actuating said switch and breaking said circuit when the elevator has 50 been raised to a predetermined position by said shaft.

7. In a sheet feeder having pneumatic sheet 55 handling means, electric motor driven pump means connected therewith, a pile elevator and a driven shaft therefor, the combination of means for supplying current to the electric motor of said pump means and comprising a circuit therefor, a switch in the circuit for breaking it to thereby stop the motor and pump and the sheet handling action of said sheet handling means, a threaded cylinder mounted on and rotated by the driven 60 pile elevator shaft, a collar mounted on said cylinder and movable therealong through rotation thereof for actuating said switch and breaking said circuit when the elevator has been raised to a predetermined position by said shaft, and means for holding said collar against rotation 65 relative to said cylinder and for guiding it during movement along the cylinder.

8. In a sheet feeder having a pile elevator including a driven shaft and means for driving said shaft to rapidly lower the elevator, means for 70 stopping said driving means and the shaft when 75

the elevator is lowered to a predetermined position, and means mounted on and actuated by said shaft for operating said second named means.

9. In a sheet feeder having a pile elevator and means for rapidly lowering said pile elevator to 5 load or reload the same, a device for stopping said means when the elevator is lowered to a predetermined position thereby, and means for actuating the stopping device comprising driven threaded means and an element movable thereby 10 along the same into engagement with said device.

10. In a sheet feeder having a pile elevator, a driven shaft therefor, and an electric motor for driving the shaft, the combination of means for supplying current to the motor comprising a circuit 15 therefor, a device in the circuit for breaking it, and means on said driven shaft movable thereby along the same and adapted to operate said device, break said circuit, and stop said motor and shaft when said elevator is moved thereby to 20 a predetermined position.

11. In a sheet feeder having a pile elevator, a driven shaft therefor, and an electric motor for driving the shaft to rapidly lower the elevator, the combination of means for supplying current 25 to the motor comprising a circuit therefor, a switch in the circuit for breaking it, a threaded cylinder mounted on and rotated by the driven shaft, and a collar mounted on said cylinder and movable therealong through rotation thereof for 30 actuating said switch, breaking said current, and stopping said motor and shaft when the elevator is lowered thereby to a predetermined position.

12. In a sheet feeder having a pile elevator, a driven shaft therefor, and an electric motor for 35 driving the shaft to rapidly lower the elevator, the combination of means for supplying current to the motor comprising a circuit therefor, a switch in the circuit for breaking it, a threaded cylinder mounted on and rotated by the driven 40 shaft, and a collar mounted on said cylinder and movable therealong through rotation thereof for 45 actuating said switch, breaking said circuit, stopping said motor and shaft when the elevator is lowered thereby to a predetermined position, and means for holding said collar against rotation relative to said cylinder and for guiding it during movement along the cylinder.

13. In a sheet feeder having pneumatic means for acting on the sheets, electric motor driven 50 pump means connected with the pneumatic means, and an elevator for the sheets raised intermittently during operation of the pneumatic means and adapted to be rapidly lowered by the electric motor for said pump means, the combination of a driven elevator shaft, a device for stopping said motor, and means mounted on said elevator shaft and movable thereby in opposite directions along the same, said means, when moved in one direction, being adapted to operate 60 said device when the elevator is intermittently raised to a predetermined position, and said means, when moved in the opposite direction, being adapted to operate said device when said elevator is rapidly lowered to a predetermined 65 position.

14. In a sheet feeder having pneumatic means for acting on the sheets, electric motor driven pump means connected with the pneumatic means, and an elevator for the sheets raised in 70 intermittently during operation of the pneumatic means and adapted to be rapidly lowered by the electric motor for said pump means, the combination of a driven elevator shaft, means for supplying current to the electric motor and comprising 75

a circuit therefor, a normally closed switch in the circuit, a threaded cylinder mounted on and rotated by the driven elevator shaft, and a collar mounted on said cylinder and movable therealong in opposite directions through rotation thereof in opposite directions, said collar, when moved in one direction, being adapted to open

thus discontinue the action of said pneumatic means when the elevator is intermittently raised to a predetermined position, and said collar, when moved in the opposite direction, being adapted to open said switch and stop the motor when the elevator is rapidly lowered thereby to a predetermined position. 5

LEO C. WILLIAMS.
